UNITED STATES PATENT OFFICE.

JOHN B. SCHNEIDER, OF DUNBAR, NEBRASKA.

WIRE FENCE.

No. 866,227.

Specification of Letters Patent.

Patented Sept. 17, 1907.

Application filed July 2, 1907. Serial No. 381,929.

To all whom it may concern:

Be it known that I, JOHN B. SCHNEIDER, a citizen of the United States, residing at Dunbar, in the county of Otoe and State of Nebraska, have invented certain new and useful Improvements in Wire Fences, of which the following is a specification.

This invention relates to certain new and useful improvements in wire fences, and has for its object to produce a fence of novel form which will so unite 10 the horizontal and vertical strands, that the utility, and efficiency of the fence will be greatly increased.

Other objects will appear in the following specification.

Referring to the accompanying drawings, Figure 1, 15 is a perspective view of a fence constructed in accordance with my invention, Fig. 2, is a fragmentary enlarged detail view in perspective showing the joint effected between the two strands, at the bottom of the fence where the horizontal strand is provided with 20 a double loop, and Fig. 3, is a like view of the barb wire which is employed at the top and bottom of the fence.

In the drawings the vertical stays are designated 1, the barbed strands 2, and the usual horizontal strands 25 3, and 3'. Vertical stays 1, at their extremities are provided with hooks 4, which closely engage the barbed strands 2, the hooks being oppositely disposed at the two ends of the stays as shown in Fig. 1. Each stay is further formed with a plurality of bent portions 30 or crimps 5, each of which is of U-shape to form abrupt right angular shoulders 6, the remainder of the stays being straight and disposed in the same plane. The horizontal strands 3, at the upper portion of the fence are each formed with a single loop 7, which engages 35 the base of the U of the crimps and is held against any tendency to move vertically by the shoulders 6, as afore mentioned, such shoulders being so located as to closely engage the top and bottom faces of the loops,

whereby a rigid connection between the stays and the horizontal strands is formed. 40

The lower horizontal strand 3', is formed with a double loop, for the purpose of strengthening the fence at this point. This double loop is designated 8, and at its top and bottom faces closely engages the abutting shoulders 6, the crimps 5, of this strand 3', being 45 formed larger than the crimps or bent portions of the upper strands 3, to receive the increased thickness of the loop 8, caused by the doubling thereof.

The barbed strands are formed of two strands of wire 9, wrapped each about the other, the barbs being 50 first looped as at 10, about one strand 9, then as at 11, about both strands conjointly, and at their ends extending in opposite directions and being pointed at their extremities.

A fence so formed presents a unitary stiff structure 55 having added strength to all points, and can be manufactured at comparative slight cost when considered from the standpoint of increased efficiency and longevity.

What I claim is:—

A fence composed of top and bottom strands of barbed wire, vertical stays having their extremities hooked to immovably engage said top and bottom strands, the said hooked portions being oppositely disposed, U-shaped crimps formed at intervals during the length of said stays, 65 said crimp having abutting shoulders, and horizontal strands, the upper of said horizontal strands being provided with a single loop which at the top and bottom faces thereof closely engage said shoulders of the crimps, and the lower of said horizontal strands being formed 70 with a double loop which at the top and bottom faces thereof engage the shoulders of the crimps at the lower ends of the stays.

In testimony whereof I affix my signature, in presence of two witnesses.

JOHN B. SCHNEIDER.
